UNITED STATES PATENT OFFICE

REMY PELTIER, OF RIVERSIDE, NEW JERSEY

DESIGN FOR A STOP LIGHT FOR AUTOMOBILES

Application filed April 11, 1930. Serial No. 35,217. Term of patent 7 years.

To all whom it may concern:

Be it known that I, REMY PELTIER, a citizen of Switzerland, having declared his intention of becoming a citizen of the United States, residing at Riverside, in the county of Burlington and State of New Jersey, have invented a new, original, and ornamental Design for Stop Lights for Automobiles, of which the following is a specification, reference being had to the accompanying drawing, forming part thereof.

Figure 1 is a face view of a stop light for automobiles, showing my new design, and Figure 2 is a side elevation thereof.

I claim:

The ornamental design for a stop light for automobiles, as shown.

REMY PELTIER.
